JOSEPH C. HERRMANN, OF MILWAUKEE, WISCONSIN.

GATE-OPERATING MECHANISM.

1,298,709.

Specification of Letters Patent.

Patented Apr. 1, 1919.

Application filed July 30, 1918. Serial No. 247,370.

To all whom it may concern:

Be it known that I, JOSEPH C. HERRMANN, a citizen of the United States, and resident of Milwaukee, in the county of Milwaukee, and State of Wisconsin, have invented certain new and useful Improvements in Gate-Operating Mechanism; and I do hereby declare that the following is a full, clear, and exact description thereof.

10 My present invention relates to new and useful improvements in means operable from a remote point for opening and closing gates particularly of that type known as farm gates, my improved operating means being more particularly of that class adapted for procuring vertical swinging movements of the gate, in opening and closing the same.

It is primarily the object of my present invention to provide a gate operating mechanism meeting the essential requirements of a commercially practical device, among which requirements may be noted: simplicity, strength and lightness of structure, readiness of operation in either opening or closing movement, and operative efficiency under adverse weather conditions.

A great many, if not the vast majority of contemplated gate operating mechanisms involving a vertical swinging movement of the gate have failed to take cognizance of the effect of lateral wind pressure upon the gate, either at rest in raised position, or in movement toward and away from raised position. Inasmuch as the lengths of gates of present character range from 12 to 16 ft. a considerable board expanse is presented to the wind, with a consequent tendency to swing the gate from alinement with its co-acting fence portions, and to impart a breaking strain on the gate pivot.

It is therefore, one important object of my invention to provide an operating mechanism for a vertically movable gate, wherein the gate body is sufficiently braced to withstand lateral wind pressure thereon in raised position, and wherein the gate will operate efficiently under the most adverse wind conditions.

A further important object resides in the provision of a gate operating mechanism having its parts arranged for movement in such manner that banking of snow adjacent the gate will not interfere in any manner with the ready operation thereof.

55 A still further object resides in the provi-

sion in a gate operating mechanism of this character adapted for use in connection with parallel stretches of fence, wherein the gate extends transversely between the fence stretches, of an arrangement wherein the fence stretches are interrupted at opposite portions of minimum width for movement of the gate ends thereinto in closing.

In common with other devices of this character, I contemplate the employment of counterweights to assist in raising and lowering movements of the gate, and inasmuch as the amount of force necessary to produce lifting movement of the gate varies considerably throughout the extent of such lifting movement, and is comparatively slight adjacent the upper limit of lifting movement, a still further object of my invention is to compensate for this variation, to insure an even operating movement of the gate, and it is particularly my object to provide an arrangement wherein the power exerted by the counterweight structure is varied in swinging movement of the gate.

A still further object resides in the provision of an operating mechanism of this character which may be most readily associated with a gate body of conventional nature.

With the above and other objects and advantages in view, my invention resides more particularly in the novel features of construction, combination and arrangement of parts which will be hereinafter described and pointed out in the appended claims.

In the drawings, the figure is a perspective view of my gate operating mechanism, with the gate in partially raised position.

Referring now more particularly to the accompanying drawings, A and B designate respectively stretches of fence extending in parallel relation beside the roadway, the stretches being interrupted at opposite portions by gate receiving spaces between pairs of adjacent fence posts.

100 My improved operating mechanism is preferably employed in conjunction with a gate body of entirely conventional nature and comprising the end rails 7, and the longitudinal top, bottom and intermediate rails, 8, 9 and 10 respectively.

105 Disposed substantially in alinement with the gate receiving portions of the fence stretches, and spaced from one of the pairs of fence posts 5 is a post 11 which is of

considerably greater height than the height of the gate. Disposed at one side of the post 11 and spaced from the adjacent fence stretch a distance substantially equal to the 5 spacing of the post 11 is a post 12 which is connected with the post 11 by suitable brace bars 13. Secured to the gate and extending outwardly from its top rail 8 in substantial alinement therewith is a rail 14 10 which is secured by a hinge 15 to the post 11 at substantially the plane of the top of the gate. Secured also to the top rail 8 adjacent its other end, which for convenience may be termed its front end, is a second rail 16 and this rail 16 extends divergently rearwardly in the plane of the gate top and is secured by a hinge 17 to the top of the post 12. A brace bar 18 extends at substantially right angles from the top rail 15 20 8 of the gate adjacent its rear end and is secured to the intersecting portion of the rail 16 and a brace bar 19 extends from a corresponding portion of the lower gate rail 9 to this securing point. A third brace bar 25 20 extends from the securing point of the other bars diagonally and inwardly with respect to the gate and is secured to the lower rail adjacent its forward end.

An exceedingly simple and practical pivot 30 mounting has thus been provided which may be readily secured to a conventional gate body. In the lowered position of the gate, its end portions are disposed between the pairs of posts 5, with the brace structure 35 disposed between the fence stretches and spaced therefrom a sufficient distance to provide clearance in upward swinging movement. The location of the gate pivot a considerable distance laterally of the fence, however, necessitates but a very slight clearance space so that the brace structure may extend throughout substantially the entire portion 40 of the gate between the fence stretches to afford a maximum strength. In the closing 45 position of the gate, the rail 16 extends above the fence stretch which it traverses, and thus the fence stretches are interrupted for distances equal only to the width of the gate body. The distance between the posts 50 11 and 12 varies in accordance with the length of gate employed, being preferably approximately one-third of the length of the gate. Thus, a pivotal connection is afforded for the gate at widely separated 55 points whereby the leverage exerted by lateral wind pressure upon the gate is reduced and whereby the gate is positively held against any lateral swinging movement, such slight movements as may occur being compensated for by upstanding oppositely curved guide arms 21 on the gate posts remote from the pivot of the gate. It will be further noted that the swinging movement 60 of the gate and all its connected parts is 65 directly upwardly. Thus the positive oper-

ation of the gate is insured, regardless of the amount of snow that may be banked there adjacent, it being noted that in lifting movement of the gate, no packing action of snow could possibly occur.

Taking up now means for procuring swinging movement of the gate, a pair of posts

70

22 are positioned along the roadway at sufficiently remote distances on opposite sides of the gate and loosely suspended from an

75

arm 23 on each of these posts, and from cross arm 24 on the top of the post 11 are pulleys 25. Cables 26 are secured to a common point at the inner portion of the top

80

rail 8 of the gate, and each is trained around one of the pulleys of the cross arm and around the corresponding pulley of one of the post arms 23 and is secured to a counterbalance weight 27.

85

Thus upon pulling downwardly upon the cable and weight, the gate will be swung upwardly to raised position.

90

Depending from each weight is a second cable 28 carrying a second counterweight 29, and the lengths of these second

95

cables 28 are such that when the gate has been partially swung to raised position, the weights 29 will rest upon the ground. Thus,

100

in the initial portions of the raising movement of the gate, the combined forces of the weights 27 and 29 are employed to assist

105

such raising movement, but in the latter portion of the raising movement, the force of the weights 27 only is employed, and thus compensation is provided for the varying

110

force required in raising the gate due to the constantly shifting leverage, whereby an even raising operation may be insured. For

115

lowering the gate, cables 30 are secured to the weights 27 and are trained about pulleys

120

31 secured to the tops of the posts 22, the remaining ends of the cables 30 being preferably attached to grip rings 32. The intermediate portion of the post 11 is provided

125

with an inwardly extending abutment 33 engageable by the gate to prevent its inward

130

swinging movement to a point at which it would be difficult to institute lowering movement of the gate. Also to facilitate the in-

135

stitution of lowering movement of the gate, a weight 34 is secured to the lower forward corner of the gate to dispose its center of

140

gravity at a maximum distance from the post when in raised position, this weight being, of course, not sufficient to add materially to the amount of force necessary in

145

raising the gate.

To prevent the cables 30 from becoming entangled whenever they are slack, and possibly, with possible displacement from their

150

pulley grooves, weights 35 are secured to their intermediate portions, being disposed adjacent the pulleys 31 on the outer stretches of the cable when the gate is raised, and serving to hold the cable taut, particularly upon engagement of the grip rings 32 with

155

the ground when the gate is lowered, such grip rings forming weights for the ends of the cables.

An exceedingly simple and durable gate 5 operating mechanism has thus been provided which may be most readily installed and which will operate efficiently even under the most adverse weather conditions. I am aware that the idea of a vertically swinging 10 gate is old, and in various types of gates heretofore contemplated, a two point pivot support may have been provided for the gate on a horizontal axis. I am not, however, 15 aware of any arrangement wherein such a support has been embodied in a gate structure particularly designed to meet the strain of lateral wind pressure under practical conditions.

While I have shown my gate as adapted 20 for closing the space between two parallel stretches of fence, it will be appreciated that the gate may as well be employed for closing a roadway gap and a single line of fence, in which instance the line of fence 25 would extend parallel to the plane of the gate and would be interrupted at the end portions of the gate when in lowered position, one of each pair of posts 5 forming the 30 end stretches and the remaining posts being idle, serving merely as guides.

What is claimed is:

1. A gate operating mechanism comprising a pair of spaced posts, hinges on said posts in horizontal alinement, a gate body, a 35 rail extending from one end portion of the gate body and secured to one of the hinges, a second rail extending from the other end portion of the gate body divergently with respect thereto toward said first named end 40 portion and projected therepast and secured to the other hinge, means connecting the intermediate portions of the second named rail with the gate body and means for raising and lowering the gate body on said hinges.

45 2. A gate operating mechanism comprising a post, a second post considerably shorter than the first named post and spaced therefrom, hinges secured to the upper end of the second named post and to the horizontally 50 alined portion of the first named post, a gate body, a rail extending from one end portion of the gate body and secured to the hinge of the first named post, a second rail extending divergently from the other end portion of 55 the gate body toward the first named end

portion and projected therepast, and secured to the other hinge, means connecting the first named end portion of the gate body with the intermediate portion of the second named rail, pulleys carried by the upper end portion of the first named post, and cables secured to the gate body and trained around said pulleys for controlling swinging movement of the gate body. 60

3. A gate operating mechanism comprising a pair of spaced posts, a pair of horizontally alined hinges carried by said posts, a gate body, a rail extending from one end portion of the gate body substantially in alinement with the top of the gate and secured to one of the hinges, a diagonal brace bar extending from the bottom of said end portion of the gate body and connected with the first named rail, a rail extending from the upper corner of the other end portion of the gate body divergently with respect to the gate body toward the first named end portion and projected therepast and secured to the other hinge, brace bars extending from the remaining corner portions of the 80 gate body to the intermediate portion of said second named rail and means for raising and lowering the gate body. 70

4. The combination with a pair of parallel fence sections having gate receiving spaces 85 therein at opposite portions of a post disposed substantially in alinement with said spaces, of a gate body having its end portions adapted to lie within the spaces of the fence stretches, a rail extending from one 90 upper corner of the gate body and hinged to the post, a second post spaced from the first post, a second rail extending from the other corner portion of the gate body obliquely over the intervening fence stretch in lowered 95 position of the gate and hinged to the second named post in horizontal alinement with the hinge of the first rail, brace bars connecting the intermediate portion of the second named rail and lower portions of the gate body, 100 said brace bars being disposed between the fence stretches in lowered position of the gate, and means for raising and lowering the gate. 105

In testimony that I claim the foregoing I have hereunto set my hand at Milwaukee, in the county of Milwaukee and State of Wisconsin.

JOSEPH C. HERRMANN.
